(57) CLAIM

We claim the ornamental design for a golf club head, as shown and described.

DESCRIPTION

FIG. 1 is a top plan view of a golf club head having surface indicia thereon.

FIG. 2 is a side elevation view from the toe side of the embodiment of FIG. 1.

FIG. 3 is a side elevation view from the heel side of the embodiment of FIG. 1.

FIG. 4 is a front elevation view of the embodiment of FIG. 1; and,

FIG. 5 is a rear elevation view of the embodiment of FIG. 1. The dashed lines in the drawings are for illustrative purpose only and form no part of the claimed design.
